Primary Examiner—Cathron Brooks*Assistant Examiner*—Rosemary Tarcza(74) *Attorney, Agent, or Firm*—Rader, Fishman & Grauer PLLC(57) **CLAIM**

The ornamental design for a battery charger, as shown and described.

DESCRIPTION

The patent or application file contains at least one drawing executed in color. Copies of this patent with color drawings will be provided by the Office upon request and payment of the necessary fee.

FIG. 1 is a perspective view of a battery charger showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
(7 of 7 Drawing Sheet(s) Filed in Color)
